UNITED STATES PATENT OFFICE.

JOHN F. A. HOOORT, OF NEW YORK, N. Y., ASSIGNOR TO THE EAST ROCKFORD MANTEL COMPANY, OF ROCKFORD, ILLINOIS.

DESIGN FOR A MANTEL.

SPECIFICATION forming part of Design No. 24,210, dated April 16, 1895.

Application filed March 21, 1895. Serial No. 542,714. Term of patent 3½ years.

To all whom it may concern:

Be it known that I, JOHN F. A. HOOORT, a citizen of the United States, residing at New York, in the county of New York and State 5 of New York, have invented and produced a new and original Design for a Mantel; and I do hereby declare the following to be a full, clear, and exact description of the same, reference being had to the accompanying drawing, forming a part thereof.

The figure of the accompanying drawing is an isometric view of the new design for mantels.

The leading feature consists of the design 15 for a mantel comprising the mantel shelf proper and two supplemental shelves one on each side the latter having approximately the form in outline of an ogee curve one part of the so called ogee having an angular shape 20 as represented each supplemental shelf being supported conjointly by a paneled frame and a single column situated immediately under the angular part of the shelf.

Numeral 1 denotes the mantel shelf and 25 numeral 2 the supplemental shelves.

3 indicates the columns partially supporting the latter shelves. These columns have each a capital 4 rounded in vertical and horizontal directions and covered with foliations. The angular portions 5 of the shelves situated 30 above the columns each present the appearance of an entablature surmounting a capital 4. Above the lateral shelves 2 near the top of the paneled frame is a centrally situated shelf 6 supported by brackets 7 and surmounted at its rear by a back 8 having on its edge foliated ornaments. 35

The mantel shelf proper is supported at each end by a column similar to the smaller columns which support shelves 2. 40

What I claim is—

The design for a mantel as herein shown and described.

In testimony whereof I affix my signature in presence of two witnesses.

JOHN F. A. HOOORT.
